UNITED STATES PATENT OFFICE.

REINHARD SCHEIDLER, OF NEWARK, OHIO.

DESIGN FOR A COMBINED BED-PLATE AND HEATER FOR PORTABLE STEAM-ENGINES.

SPECIFICATION forming part of Design No. 12,676, dated January 10, 1882.

Application filed October 10, 1881. Term of patent 7 years.

To all whom it may concern:

Be it known that I, REINHARD SCHEIDLER, a citizen of the United States, residing at Newark, in the county of Licking and State of Ohio, have invented and produced a new and original Design for a Combined Bed-Plate and Heater for Portable Steam-Engines, of which the following is a specification, reference being had to the accompanying drawings, forming a part thereof.

Figure 1 is a side elevation of my combined bed-plate and heater, the engine seated thereon being shown in dotted lines. Fig. 2 is an end view of the same, seen from the left without the engine, showing also a partial outline of the boiler.

In the drawings, A is the heater, which has a flat top surface. The whole of the heater, including the bracket α , constitutes my design.

The part α includes one-half of the box for the

shaft. The general contour of my heater and bed-plate is oblong, having parallel sides and a triangular cross-section, or nearly so, as seen in the end view in Fig. 2. The cylinder (seen in dotted lines) and the yoke are both shown 25 on the heater, while the latter occupies in its length a distance equal to the extreme length of the engine proper.

I claim—

The design for a combined engine-bed and 30 heater of oblong shape, and triangular, or nearly so, in cross-section, with the bracket α , forming the vertically-divided one-half of the main driving-shaft box, as hereinbefore shown and specified.

REINHARD SCHEIDLER.
